UNITED STATES PATENT OFFICE.

JOHN KILGORE JOHNSTON, OF TYRONE, PENNSYLVANIA.

RAILROAD-SIGNAL.

No. 885,621.

Specification of Letters Patent.

Patented April 21, 1908.

Application filed July 26, 1906. Serial No. 327,851.

To all whom it may concern:

Be it known that I, JOHN KILGORE JOHNSTON, a citizen of the United States, and a resident of Tyrone, in the county of Blair 5 and State of Pennsylvania, have invented a new and Improved Railroad-Signal, of which the following is a full, clear, and exact description.

This invention relates to certain improvements in railroad signals, whereby the same signals which are employed in the day time may be employed at night, and all danger arising from the failure of the engineer to distinguish between the different colored lights 15 is eliminated.

According to this invention the signals are given by semaphore arms, and means are provided whereby the position of these arms may be very clearly seen even on the darkest 20 night.

Reference is to be had to the accompanying drawings which form part of this specification, in which drawings like characters of reference indicate like parts throughout the 25 views, and in which

Figure 1 is a side elevation of but one end of a standard railroad signal bridge with semaphore signals as they appear to approaching engines; Fig. 2 is an end elevation 30 thereof; and Fig. 3 is a horizontal section through one form of screen which I may employ.

The bridge shown in the drawings is of standard design and extends across the railroad tracks, and supports a semaphore signal above each of said tracks. The semaphore signal arms 1 are supported upon the signal poles 2, and the position of these arms may be varied to indicate different conditions to 35 the engineers on approaching trains. In order that these signals may be seen at night, I provide a screen 3 composed of slats 4 of wood, canvas, metal or any suitable composition having interstices or perforations therebetween, whereby the air may freely pass 40 through the same and thus reduce the liability of the screen being blown down during a storm. Each slat is covered with paint, enamel, pigment or other substance which 45 will reflect and break up the light rays from the lamps, whereby the entire screen will present a large illuminated surface. To light up the screen I provide a plurality of oil or incandescent lamps or arc lights 5 upon 50 the back side of the signal poles 2, in such a position that the lights themselves cannot

be seen from approaching trains, but the exposed screen is brightly illuminated. The signal arms are supported on the dark side of the poles, and are unaffected by the lights, 60 but as the arms are moved in front of the screen the contrast between the dark arm and the brightly light screen is very decided and the position of the arm may be determined with the greatest ease.

My improvement can be applied to bracket post, ground post, distant, route, home, block, interlocking, dwarf or disk signals where standard signal bridges are not in use.

In my improved railroad signal above described, there are no bright lights directed toward the approaching trains to blind the eyes of the engineers, and the signal being given by the position of the arm rather than by the color of the light, or colored lights in 75 combination, accidents due to color blindness or mistaken interpretation of the engineers are entirely out of the question. Furthermore, the same signals employed in the day time are employed at night, and operated in 80 exactly the same way, thus obviating the expense of providing two entirely separate and independent systems of signals, one for use in the day time and one for use at night.

Having thus described my invention, what 85 I claim as new and desire to secure by Letters Patent is:

1. In combination, a substantially vertical screen constructed to permit the passage of air therethrough, a signal arm adapted to be 90 moved in front of said screen, and means for illuminating the side of the screen toward the signal arm and the rear side only of the signal arm.

2. In combination, a screen constructed to 95 permit the passage of air therethrough and having a surface covered with a light reflecting substance, a semaphore signal arm adapted to be moved in front of said screen, and means for illuminating the screen the arrangement being such that the face of the arm away from said screen remains unilluminated.

3. The combination with a signal arm, of an opaque screen supported therebehind, and 105 means arranged between the screen and the signal arm for illuminating the screen, said means being directed toward the screen and shielded from an observer in front of the signal arm for the purpose set forth.

4. The combination with a signal pole provided with movable signal arm, of an opaque

screen arranged behind the signal arm, and means connected with the pole on the side of the pole toward the screen for illuminating said screen, the pole concealing said illuminating means from an observer in front of the screen.

In testimony whereof I have signed my

name to this specification in the presence of two subscribing witnesses.

JOHN KILGORE JOHNSTON.
